M. E. BUCK,
WIRE STRETCHER,
APPLICATION FILED MAR. 31, 1919.

1,396,502.

Patented Nov. 8, 1921.

Inventor

Milton E. Buck

By Attorneys.

UNITED STATES PATENT OFFICE.

MILTON E. BUCK, OF EMATON, KANSAS.

WIRE-STRETCHER.

1,396,502.

Specification of Letters Patent.

Patented Nov. 8, 1921.

Application filed March 31, 1919. Serial No. 286,298.

To all whom it may concern:

Be it known that I, MILTON E. BUCK, a citizen of the United States, residing at Ematton, in the county of Stevens, State of Kansas, have invented certain new and useful Improvements in Wire-Stretchers; and I do hereby declare the following to be a full, clear, and exact description of the invention, such as will enable others skilled in the art to which it appertains, to make and use the same.

This invention relates to new and useful improvements in wire stretchers, and particularly to such devices as are arranged to be secured to the fence post.

One object of the present invention is to provide a novel and improved device of this character which is simple and cheap in construction and durable and efficient in operation.

Another object of the present invention is to provide a novel and improved winding drum for a device of this character which can be easily and quickly taken apart for cleaning and repairs, and which can be easily and quickly put together.

Other objects and advantages will be apparent from the following description when taken in connection with the accompanying drawing.

In the drawing:

Figure 1 is a side elevation of the invention in operative position.

Fig. 2 is a top plan view of the same.

Fig. 3 is a vertical longitudinal sectional view taken on the line 3—3 of Fig. 2.

Fig. 4 is a vertical transverse sectional view taken on the line 4—4 of Fig. 2.

Referring particularly to the accompanying drawing, 10 represents a yoke member the outer ends of the arms of which are formed with the eye portions 11. Secured movably to the intermediate portion of the yoke member is a tongue 12 having side notches which produce the hooks 14 for engagement by the end links of the chain 15. This chain is clearly shown in the drawing to be engaged around the fence post 16, whereby the member 12 and the yoke are held in proper position. A drum 17 has the end portions of its body journaled in the eye portions 11 of the yoke arms, as shown. One head of the drum is in the shape of a fixed peripheral flange 19 provided with ratchet teeth 18. This flange is arranged outwardly of the adjacent eye

portion. The other end of the drum is counterbored with a cavity 20 in one side of which there is formed a longitudinally extending notch 22 for the reception and retention of one end of the stretcher chain 23. The other head of the drum is made up of a disk 21 about the same size as the flange 19, and a boss 21' projecting rigidly from the disk and of a size to enter the counterbored end of the body of the drum, so that when in place therein it will close the notch 22 as seen in Fig. 2. Formed longitudinally through the drum is a bore 24, which is preferably angular in cross section, and fitted into this bore is a correspondingly shaped shaft 25, one end being secured by means of the transverse pin 27, while the other end portion is formed with a stop shoulder 25' which engages against the before-mentioned disk 21. Outwardly of the shoulder 25' there is formed a T-head 26, on the shaft 25, from which extend the radially disposed handle members 28, which are adapted to be grasped to rotate the shaft 25, to wind the chain 23 on the drum. The other end of the chain 23 is provided with a wire gripping clamp 23' for engagement with the fence wire 30.

Pivottally supported on one of the arms of the yoke is a pawl 29 which engages with the teeth 18 to prevent retrograde rotation of the drum, while winding the same to stretch the wire 30.

From the foregoing it will be apparent that the chain 15 is engaged around the fence post and the end links engaged with the hooks 14, to hold the yoke member in proper position. The handle members 28 are then grasped and the shaft and drum turned to wind the chain 23 thereon, with the result that the wire 30, which is engaged with the clamp 23', is stretched, and the same can then be secured to the post by means of a staple, as will be readily understood.

What is claimed is:

1. A winding drum whose body is provided with an axial bore of angular cross section and counterbored in one end to produce a cavity, the other end of the body being enlarged to form one head and provided with peripheral teeth, a second head composed of a boss of a size to fit the counterbore and a disk larger than the boss, a shaft through the elements of the second head and the bore of the body, bearings in

which the device is mounted, means for turning the shaft, and retaining means engaging said teeth.

2. In a winding drum, the combination 5 with a yoke having bearings in its arms, and a detent pivoted to said yoke; of a drum whose body is rotatably mounted in said bearings and has a cavity in one end and an enlarged head at the other end provided 10 with teeth to engage said detent, a second head having a boss of a size to enter said cavity, a shaft fixed through the second head and body, and operating means for the shaft.
- 15 3. In a wire stretcher, the combination with a support, a yoke connected therewith and having bearings in its arms, a detent carried by one of the arms, and a chain; of a drum whose body is mounted in said bearings and counterbored in one end to produce 20 a cavity, the wall of the cavity having a notch opening out its end for the engagement of a link of said chain, an enlarged head at the other end of the drum peripherally toothed for engagement with said 25 detent, a head for the open end of the drum adapted when in position to close said notch, a shaft extending completely through the

drum and having a shoulder against one head and fastening means against the other, 30 and handles on one end of the shaft.

4. In a wire stretcher, the combination with a support having spaced eyes, and a detent carried by the support; of a drum whose body is journaled in said eyes and 35 has a cavity in one end with a notch in one wall of the cavity, a head at the other end of the body consisting of a fixed peripheral flange thereon provided with teeth for engagement with said detent, a head for the 40 open end of the body consisting of a disk having an integral boss of a size to enter the cavity and to close the open end of said notch, both heads and the body having angular axial openings, a shaft of a size to 45 fit said openings, means on the shaft for engagement with the heads, operating means on one end of the shaft, and a winding chain adapted for engagement with said slot.

In testimony whereof, I affix my signature, in the presence of two witnesses.

MILTON E. BUCK.
